UNITED STATES PATENT OFFICE.

JULIUS SWANBERG, OF CHICAGO, ILLINOIS, ASSIGNOR TO THE SWANBERG COMPANY,
A CORPORATION OF ILLINOIS.

AUTOMATIC FIRE-ALARM.

1,367,899.

Specification of Letters Patent.

Patented Feb. 8, 1921.

Application filed May 31, 1919. Serial No. 300,854.

To all whom it may concern:

Be it known that I, JULIUS SWANBERG, a citizen of the United States, and a resident of the city of Chicago, in the county of Cook and State of Illinois, have invented certain new and useful Improvements in Automatic Fire-Alarms; and I do hereby declare that the following is a full, clear, and exact description of the same, reference being had to the accompanying drawings, and to the numerals of reference marked thereon, which form a part of this specification.

My invention has reference more particularly to an improved individual fire alarm device, which is adapted to be constructed in a portable form, and is arranged to be automatically set in operation when exposed to a temperature above a predetermined degree.

Fire alarm devices such as are used at the present time, are usually connected in a fire alarm or protective system to be controlled or operated from a distant point or outside source of energy, and are not only complicated and expensive to install and maintain in working condition but are not independent and readily transferable from place to place so that they are within the means of average users and capable of being located in any desired place at will.

The object of my invention is to provide a simple and effective individual fire alarm device which may be readily mounted in any convenient place.

Another object of my invention is to provide a device of this character having improved mechanism for ringing a gong and which is adapted to be automatically set in operation by increase in temperature above a predetermined degree.

Another object of my invention is to provide a fire alarm device with improved means, releasable by heat, normally holding the alarm mechanism from operation.

My invention also has other important objects which will appear from the following specification and the accompanying drawings in which I have described and illustrated my invention in a preferred form.

On the drawings:

Figure 1 is a front view of a device constructed in accordance with my invention.

Fig. 2 is a back view of the device.

Fig. 3 is a side view of the device.

Fig. 4 is a vertical sectional view on the line 4—4 of Fig. 1.

Fig. 5 is a sectional view on the line 5—5 of Fig. 4.

Fig. 6 is a front view of the device with the gong removed.

Fig. 7 is a sectional view on the line 7—7 of Fig. 4.

Fig. 8 is an enlarged fragmentary sectional view on the line 8—8 of Fig. 5.

Fig. 9 is an enlarged vertical longitudinal view of the spindle that supports the gong.

Fig. 10 is an enlarged front view of the knob that holds the gong in place showing the releasable disk for holding the ringing mechanism inoperative.

Fig. 11 is a side view of a modified form of construction.

Fig. 12 is a front elevation of the device shown in Fig. 11.

Fig. 13 is a top plan view of a part of the same device.

Fig. 14 is a section on the line 14—14 of Fig. 13.

As shown on the drawings:

The reference numeral 1, indicates a casing of circular form having front and rear walls 2 and 3, respectively, secured together in any convenient manner, for example by the pins or bolts 4, and spacing ferrules 5, as shown. A frame plate 6, is secured diametrically within the casing between the front and rear walls 2 and 3, and there is a short spindle 7, journaled centrally in the casing in the frame plate 6 and rear wall 3. A ribbon spring 8, is coiled about the spindle 7, and attached thereto at its inner end and the outer end is attached to one of the pins or bolts 4.

Secured on the front end of the spindle 7, is a ratchet wheel 9, and a large gear wheel 10, is mounted loose on the spindle between the ratchet wheel 9, and frame plate 6, and has a spring impelled pawl 11, pivoted thereon to engage the ratchet wheel 9, so that rotation of the spindle 7, in one direction operates the large gear with it and in the other direction does not rotate the large gear. The large gear meshes with a pinion 12 on a shaft 13, mounted in the front wall 2 and frame plate 6, and thereby operates an escapement wheel 14, which operates an escapement lever 15, fixed on a shaft 16, extending through the front wall 2, of the casing.

A pendulum 17, is pivoted to the upper part of the front plate 2, to swing so as to

strike a gong 18, covering the front of the device, at each end of its oscillating movement, and has a link 19, pivotally connected therewith near to the pivot thereof and connected with a long arm 20 which is secured to the spindle 16, to oscillate therewith. The connection of the link 19, with the pendulum is offset slightly at one side thereof so as to avoid a dead center when the pendulum is in 10 the normal inactive position and enables the escapement mechanism to initiate swinging movement of the pendulum.

A bell supporting post 21 is secured to the center of the front wall 2, and extends forwardly therefrom. The outer end is shouldered to receive the bell 18, thereon and is also threaded beyond the shoulder to have a knob or nut 22, turned thereon for holding the bell in place.

20 This post 21 is also bored out longitudinally to have a pin 23, mounted thereon to reciprocate, and has a slot 24 in the side wall through which a pin 25, projects. The knob 22, is constructed to hold the pin inwardly 25 against the tension of a spring 26, which is compressed by the pin 23 against the bottom of the opening in the post 21, and when so positioned the pin 25 engages an arm 27 of the lever, 20 at such a position to permit the 30 pendulum 17 to hang freely and prevents operation thereof by the escapement mechanism.

For winding the spring 8 so that the device is capable of operation, the spindle 7 35 has a socket 28 in the rear end or is otherwise constructed to be engaged by a wrench or key, and to enable the operator to determine the extent to which the spring is wound, I have provided a radial slot 30 in 40 the rear wall 3, having a mark 31 at the side to indicate the proper contracted position of the spring for full winding. This slot may be covered with a transparent covering if desired to protect the mechanism inside 45 the case. The back plate 3, is also provided at the top with a perforated ear 32, so that the device may be conveniently hung on a nail or hook.

For affording release of the pin 23, at the 50 proper time to permit operation of the alarm, the knob 22, is provided with a disk 33, which is secured to the front of the knob by solder 34, or other preparation which fuses or melts at the desired temperature, and the 55 outer end of the pin 23, bears against this disk so that when the latter is released the pin is free to move under the tension of the spring 26. In order to render the solder or material which holds the disk 33 in place 60 highly sensitive to the heat, and prevent diffusion of heat therefrom, a bushing 35 composed of heat non-conducting material is secured in the outer end of the knob 22, and has a ring 36 of metal embedded therein to 65 which the solder or other fusible material

will adhere. The outer end of the pin 23, is also constructed with an insert or tip 37, of heat non-conducting material, which engages the plate 33, so that the plate 33, ring 36, and solder or fusible connecting material 34, is isolated from any metal that would diffuse the heat absorbed thereby, and thus renders the controlling mechanism highly sensitive.

In Figs. 11 to 14 is shown a modified form 75 of device for affording release of the pin 23, when the predetermined temperature has been reached. In this case release is obtained by means of a pair of overlapping plates 40 and 41 secured together by suitable fusible material. These plates are preferably formed so that when connected as shown in Fig. 14, they form a diamond. The advantage of this shape is that a relatively large overlapping area is obtained 85 while at the same time the conduction of heat from the plates is a minimum owing to the fact that they are supported by their pointed ends only.

The end of one plate, as 41, bears against 90 the heat insulator 37, in the end of the plunger 23. The end of the other plate 40 engages a recess in the central part of a cage 42, conveniently formed of two strips of metal crossing each other at right angles. The 95 ends 44 of these strips are passed through apertures in a heat insulating plate 43 and clenched on the opposite side. This heat insulating plate is threaded onto the end of the post 21.

Between the end of the heat insulator 37 and the plate 41 is arranged a strip of metal 45, indented at 46, at its center for the reception of the end of the plate 41, and forked at its ends 47 for engagement with 105 shoulders 48, on two diametrically opposite members of the cage 42.

Another advantage of the construction shown in Figs. 11 to 14 is that free access of air is permitted to the plates 40 and 41 110 through the cage 42, so that the device is very sensitive to temperature changes and will operate as soon as the surrounding air has reached the predetermined temperature.

The operation is as follows:

In the form of construction shown in Figs. 1 to 10, the knob 22 is secured on the end of the post 21 with the plunger 23 pressed thereby inwardly against the tension of the spring 26.

With the device shown in Figs. 11 to 14, the diamond, formed of the plates 40 and 41 is inserted between the cage and the end of the plunger 23, which is thereby pressed inward and held in that position.

When the plunger 23 is pressed inward, the pin 25 engages the arm 27 of the oscillating lever 20, to prevent operation of the escapement mechanism, the pin 25 being enabled to pass over the arm 27, in this set- 130

ting operation by turning the entire device so that the pendulum 17 hangs in a position to hold the lever 20 and arm 27, so that the pin 25 will clear the latter. The gong 18 is, of course, mounted on the post 21 previous to the attachment of the knob 22 so that the latter, when screwed down in place, will hold the gong on the post.

The spring 8 is then wound by turning the spindle 7 in the direction indicated by the arrow in Fig. 5, with a key or suitable tool, the degree of winding being observed through the slot 30 in the back of the device. The winding of the spring rotates the ratchet 9, permitting the pawl 11 to ride over the teeth thereof, and as the gear 10, to which the ratchet pawl 11 is attached, is geared to the escapement mechanism and the latter held from operation by the engagement of the pin 25 with the arm 27, back movement of the ratchet wheel 9 is prevented and the spring held in the wound condition.

The device is then hung on a nail or hook in any desired location, and upon the occurrence of a fire, the rise in temperature above the predetermined point at which the solder or other material 34 fuses, melts the latter and releases the disk 33, whereupon the pin 23 is projected forwardly by the spring 26 and moves the pin 25 along the slot 24, away from engagement with the arm 27, thus releasing the arm 20 so that it may be operated by the spring powered escapement mechanism and swing the pendulum hammer 17 to strike the gong.

It will be observed that the pendulum acts as a governor to control the operation of the escapement mechanism and is arranged to strike the gong at each end of its oscillation so that the maximum of efficiency is attained and the alarm will continue for a long period before the power of the spring is exhausted.

I am aware that various details of construction may be varied through a wide range without departing from the principles of my invention and I therefore do not purpose limiting the patent granted further than necessitated by the prior art.

I claim as my invention:

1. A fire alarm comprising an alarm device, a member retractable against the tension of a resilient element for holding said device inoperative and means for holding said member in retracted position adapted to be released by exposure to a predetermined temperature including a diamond-shaped member formed of a pair of overlapping

plates secured together by fusible material 60 adapted to bear at diametrically opposite corners on the indicating device and retractable member respectively.

2. A fire alarm comprising an alarm device, a member retractable against the tension of a resilient element for holding said device inoperative and means for holding said member in retracted position adapted to be released by exposure to a predetermined temperature including a cage secured 70 to the indicating device, and surrounding the end of the retractable member, and a diamond-shaped member formed of a pair of overlapping plates secured together by 75 fusible material adapted to bear at diametrically opposite corners on the cage and retractable member respectively.

3. A fire alarm comprising an alarm device, a member retractable against the tension of a resilient element for holding said device inoperative, and means for holding said member in retracted position adapted to be released by exposure to a predetermined temperature including a cage surrounding the end of the retractable member, 85 a heat insulating member secured to both the alarm device and said cage to prevent passage of heat from the latter to the former, a heat insulating contact member on the end of the retractable member and a 90 pair of members secured together by fusible material between the cage and the said contact member.

4. A fire alarm comprising an alarm device, a member retractable against the tension of a resilient element for holding said device inoperative, and means for holding said member in retracted position adapted to be released by exposure to a predetermined temperature including a cage surrounding the end of the retractable member, 95 a heat insulating member secured to both the alarm device and said cage to prevent passage of heat from the latter to the former, a heat insulating contact member 100 on the end of the retractable member and a diamond-shaped member formed of a pair of overlapping plates secured together by 105 fusible material adapted to bear at diametrically opposite corners on the alarm device 110 and said contact member respectively.

In testimony whereof I have hereunto subscribed my name in the presence of two subscribing witnesses.

JULIUS SWANBERG.
